(57) **CLAIM**

The ornamental design for a display screen with animated graphical user interface, as shown and described.

DESCRIPTION

FIG. 1 is a front view of a display screen with animated graphical user interface showing my new design; and, FIG. 2 is a front view of a second image thereof.

The appearance of an image sequentially transitions to another between FIG. 1 and FIG. 2. The process or period in which an image transitions to another forms no part of the claimed design. The outermost dot-dash broken lines depict the display screen and form no part of the claimed design. The remaining dot-dash broken lines depict portions of the animated graphical user interface that form no part of the claimed design. The dotted broken lines depict portions of the animated graphical user interface that form part of the claimed design.
